UNITED STATES PATENT OFFICE

JACOB L. KLEINMAN, OF NEW YORK, N. Y.

TENNIS RACKET

Application filed September 4, 1929, Serial No. 390,384. Renewed September 19, 1932.

This invention relates to tennis rackets and more particularly to rackets of the adjustable type.

A primary object of the invention is to provide a racket with means for readily adjusting the tension of the strings.

A further object is to provide an adjustable racket having certain parts built of metal and reinforced with other material which keeps the strings out of contact with the metal portions.

It is also an object of the invention to provide means to receive the shock and prevent vibration of the tensioning device in the racket when in use; to provide a racket of the open-throat type having means for adjusting the tension of the strings; to provide a racket having reinforcing means at its neck portion and also around the frame and handle; to provide a racket with a reinforced handle; to provide a racket having a handle with gripping means thereon composed of a material different from that of the handle, to prevent the turning of the racket in the hand of the player when hitting a ball; to provide a racket having the bottom of the handle reinforced with a strong material having a neat and pleasing finish; and to provide a racket of the adjustable type, that is practical, useful, durable in use, simple in construction, and convenient and economical to manufacture.

Other objects and advantages of the present invention will appear from the description thereof to follow taken in connection with the accompanying drawing in which—

Fig. 1 is a front view of a racket embodying my present invention, partly broken away at the bottom of the handle and also at the neck portion to reveal the internal structure.

Fig. 2 is a cross sectional view showing the reinforcement of the frame, particularly at the neck portion, and is taken along the line 2—2 of Fig. 1.

Fig. 3 is an enlarged view of the string supporting member, partly broken away.

Fig. 4 is a cross-sectional view of the string supporting member taken along the line 4—4 of Fig. 3.

Fig. 5 is a cross-sectional view on the plane indicated by the line 5—5 of Fig. 1.

Fig. 6 is a modified form of the gripping surface of the handle.

Fig. 7 is a sectional view showing the beaded or ribbed portions of the bottom of the handle and is taken along the line 7—7 of Fig. 1.

Referring to the drawing, 5 indicates the frame, and 6 the handle of the racket, the frame and handle being formed in sections, as is usual. At the throat or neck portion of the racket is a substantially triangular opening 7. Slots 8 are formed at the inner walls of the portions of the frame defining said neck portion. A bridge 9 having offset portions or tongues 10 is positioned in said frame the offset portions 10 being fitted snugly, and if desired also glued, within the slots 8. Holes are drilled through the said neck portions of the frame and the offset portions 10, and rivets or pins 11 inserted in said holes, thereby forming a rigid structure of the type known in the trade as an open-throat racket.

It is a well known fact that the most important consideration in the design of a racket is its weight. A racket must be as light as possible, and the manufacturer, in order to meet the demands, makes his frame as thin as he can; the strength of the racket frame is therefore sacrificed for lightness, and consequently frequently breakage results. Manufacturers have therefore tried to glue a piece of fiber or rawhide on the side of the neck portion to strengthen the racket, but this has proved unsatisfactory because it has been found that glue does not form a strong and continuous bond between wood and fiber, because as the glue dries it shrinks away from the fiber and a space is left between the wood

and fiber, particularly along the peripheral edge of the frame, such space not only weakening the bond between the wood and fiber, but making the racket unsightly.

5 In order to overcome this difficulty and to build a strong racket which is yet as light in weight as is required, I provide slots or openings 12 at the neck portion of the frame. These slots may be extended to any point of 10 the frame, or handle, or all around the frame, if so desired. I then fit a piece of fiber, raw hide, or any other suitable material, tightly into the slot, as indicated at 13 in Fig. 2. I also form grooves 14 in the inner and outer 15 walls of the frame, down to and into the handle to the point indicated at 15, or lower if so desired, and I place in these grooves fiber, raw hide, or any other suitable material as indicated at 16. These pieces 16 and 13 respectively are glued and pressed tightly into these 20 slots or grooves by a press or clamp to wedge the fibre within the grooves. Consequently, when the glue dries, the wood and insert will not come apart, as the walls of the slots or 25 grooves tightly engage the walls of the inserts. If desired, holes may be drilled and a rivet or pin 17 may be inserted and both ends thereof flattened at 18 to assure against displacement of parts. I desire it to be understood that instead of constructing the racket 30 with an open-throat, as illustrated in the drawing, the racket may be provided with a filler block or element in the opening 7.

Referring to Fig. 1, when the bridge portion 9 is secured to the frame it forms a part 35 of the frame. A slot 19 about $\frac{7}{8}$ " deep is provided in said portion 9 and receives a string supporting member or tensioning device 20. A hole 21 is formed in the bottom 40 wall of bridge 9 and through such holes passes a rod or bar 22 which is pivotally secured to a lug 23 extending from member 20, by a rivet or pin 24. The remaining part of the 45 racket handle, the rod extending below a shoulder 26 and in spaced relation to the wall 27 of an enlarged chamber 28 which forms a continuation of chamber 25.

A handle of a racket generally consists of 50 two sides 29 and 30 which are a continuation of the frame 5 (Fig. 5), and two separate pieces 31 and 32 which are usually glued to the sides 29 and 30. I provide a metal portion or plate 33 having teeth 34 by which it 55 is attached to the shoulder 26. When the frame is built and chambers 25 and 28, slot 19 and hole 21 are formed, the rod 22 is put through the hole 21 and chamber 25 and into chamber 28. Plate 33 is then placed into 60 chamber 28, permitting the lower, cylindrical end of rod 22 to pass through its round hole 35 with which communicates a rectangular slot 36, forming a key-hole slot. The plate 33 is moved upwardly and the rod 22 is shifted to cause its intermediate flattened portion

37 to enter the slot 36, after which the plate 33 is attached by pressure to the shoulder 26. Thus the plate 33, having its teeth deep in the shoulder 26 which is formed of the parts or pieces 29, 30, 31 and 32, holds these parts together, thereby forming a strong structure at this point and at the same time preventing the displacement or rotation of rod 22, the hole 35 being against and covered by the shoulder 26. In order that slot 36 may not injure rod 22, the edges 38 are bent downwardly and away from each other, thus providing a rounded smooth surface for rod 22, which exerts no abrasive action upon the rod during the latter's up and down movements as described hereinbelow.

In order to provide good gripping means at the handle so that the racket will not turn in the hand of the user, I cut or shape away some of the wood at the bottom of the handle as at 39 to such depth as may be desired, thereby forming a portion of smaller diameter than the rest of the handle. I then put glue on said reduced portion and force tightly over it a tubular form of sleeve 40 made of cork or other suitable material; I then take a cover 41 made of hard material having its walls smoothly finished and force the same tightly on the end of portion 39 so as to cover its edge, the cover reinforcing the bottom of the handle and holding the tubular form in place. I then take an internally threaded tubular element 42 which is preferably closed at one end and embedded in a bakelite cap 43 having a tapered extension 44, a flat surface 45 for engaging the cover 41, a side wall 46, and a hollow cup form 47. The outside of wall 46 as indicated at 48, is of a smooth finish, as shown at 49 (Fig. 7) and is provided with ribs or beads 50, spaced apart from each other, and also a horizontal flange or bead 73. The ribs 50 serve to provide a non-slipping surface when the cap 43 is grasped by the hand and rotated. The insert 42 has grooves 51 and 52 and beads, heads or shoulders 53 and 54, to cause the bakelite or other molding material to interlock with said insert 42, as at 55, thereby forming a rigid unitary structure. As will be seen from Fig. 1, either the under surface of cover 41 or the upper surface of cap 43, or both, are dished, so that the cover and cap engage only at their peripheral portions, so that friction between the parts is greatly reduced. In order further to reduce the effort required to rotate cap 43 to adjust the strings (as described below) I make the extension 44 tapered, so that while its bottom portion snugly engages the inner portion of cover 41 it is spaced for the greater part of its length from the internal parts of the handle.

Referring to Figs. 3 and 4, the string supporting member 20 has a metal insert 56 formed with holes 57 and 58. Insert 56 is also formed with corrugations or grooves 59

which act to stiffen and strengthen said insert 56 and to prevent the same from flexing or bending. The corrugations 59 also act as interlocking means for the covering 60, 61, 5 which is of molded bakelite. Holes 58 permit the coverings 60 and 61 to be connected as at 62 and become one solid structure, thereby preventing the covering from falling off the insert 56. It will be noted that the holes 10 57 of the upper row are not, like the holes of the lower row completely filled with bakelite, but have their edges covered with the molding material, as shown at 63 and 64, thus leaving holes 65 of a desired small dimension 15 for receiving the strings. The strings are thus kept out of contact with the sharp edges of the metal insert 56.

When the racket is all completed and assembled as in Fig. 1 the strings are then 20 mounted. The horizontal strings 65' are mounted in the usual manner, but the vertical strings 66 which form the playing field in the center of the racket, are threaded through the holes 65 in the member 20, which 25 is attached to rod 22 whose extreme end 67 is threaded to engage the internal thread of the tubular element 42, with the result that, if the racket is held in one hand the other hand grips and turns the cap 43, the rod 22, which is unable to turn on account of its flat portion 37 fitting in rectangular slot 36, is then pulled downwardly by the member 42. The member 20 is thus also pulled downwardly, thereby tightening the strings in the 35 frame. By turning portion 43 in a reverse direction, the strings will be loosened.

I also provide means to receive the shock or vibration of rod 22 and member 20 during play, consisting of a cork portion 68, Fig. 1, 40 attached to the bridge 9 by a screw 69. The rod 22 fits snugly in the hole 70 of the portion 68; and as the latter is made of cork (or other resilient material or element), vibration of the rod 22 and member 20 will be 45 eliminated.

In the hand of a fast player quite often the racket will twist, turn or slide. To prevent this, I provide the tubular portion or sleeve 40 with vertical or horizontal ribs or beads 71 (Fig. 6) or 72 (Fig. 1), similar to the ribs or beads 50 (Fig. 7) so that when the player takes hold of the racket, the palm of his hand will engage the beads and fill the spaces between the beads, so that the player would then have a firm hold of the racket and be able better to control the same.

Cap 43, Fig. 1, may also be fitted onto a plain racket, i. e. one not having the string 50 adjusting feature, to take the place of the ordinary leather strip at the bottom of the handle. Being made of bakelite, it can be of various colors and designs to provide an 55 ornamentation for the racket, and at the same time forming a reinforcement for the

bottom of the handle, and providing additional gripping means for the hand.

Although I have mentioned in describing my invention of what materials certain parts may be made, yet I desire it to be understood 70 that this racket, or parts thereof, may be made of any suitable material and that various changes in details may be resorted to without departing from the spirit of the invention and I desire to be limited only by the 75 state of prior art.

I claim—

1. In a racket, a frame, a handle, a string tensioning device mounted in said frame, shock absorbing means engaging said frame 80 and said tensioning device, and means for operating said tensioning device.

2. In a racket, a frame, a handle, and a string tensioning mechanism, including a rod positioned in said handle, and operating 85 means comprising a rotatable element at the end of said handle and cooperating with said rod, the lower end of said rod being threaded and said element being composed of a molded composition and having embedded therein a 90 member closed at its lower end and threaded at its upper end to engage with the threaded end of the rod.

3. In a racket, a frame, a handle, and a string tensioning mechanism, including a rod 95 positioned in said handle, operating means comprising a rotatable element at the end of said handle and cooperating with said rod, an intermediate portion of said rod being non-circular, and an insert anchored within 100 said handle and provided with a non-circular opening to receive the said intermediate portion of the rod to prevent rotation of the latter upon operation of said rotatable element.

4. The structure as set forth in claim 3 105 wherein said opening is in the form of a key-hole slot, and means whereby the circular portion of said slot is closed after insertion of said rod.

5. The structure as set forth in claim 3, 110 wherein said handle is composed of longitudinal sections at least two or which are provided with internal shoulders, said insert being anchored in said shoulders to hold said sections together.

6. In a racket, a frame, a handle, strings stretched within said frame, at least a portion of the string-anchoring parts of the racket consisting of metal embedded in a 115 non-metallic plastic body.

7. In a racket, a frame, strings within said frame, a handle, a metallic string tensioning device positioned within said frame, and engaging certain of said strings, a portion of 120 said device covered with a hard wear-resisting coating providing a smooth seating for the strings, and means for operating said device.

8. In a racket, a frame, a handle having an 125 annular end portion, and a string tensioning 130

- device positioned in said handle, and operating means comprising a rotatable element at the end of said handle and cooperating with said device, said end portion and element being formed to bear against each other with line contact only, said line of contact forming a circle.
9. In a racket, a frame, a handle, a metallic string tensioning device positioned in said frame, said device provided with an irregular surface forming a seat for a coating and means for tensioning said device.
10. In a racket, a frame having strings stretched across the same, a hollow handle, a string tightening longitudinally movable member disposed in said handle, a movable hand-grip portion, and means in mortise and tenon connection with said hand-grip portion adapted to engage the said member and effect adjustment of the latter upon movement of such hand-grip section.
11. In a racket, a frame, strings within said frame, a hollow handle having an end section, a longitudinally movable member disposed in the hollow of said handle and engaging certain of said strings, a second member being in screw threaded connection with said first mentioned member, said second member provided with at least one shoulder portion, said second member positioned within a rotatable cup-shaped member, said rotatable member connected with said second member by means cooperating with said shoulder, said cup-shaped member engaging said end section thereby closing the hollow of said handle.
12. In a racket, as set forth in claim 10, wherein said hand-grip section is composed of a molded composition and wherein said means is embedded therein.
13. In a racket, as set forth in claim 10, wherein said means comprises a threaded element projecting inwardly of the handle and engaging the threaded end of said member.
14. In a racket, a frame, a hollow handle, a neck portion, strings supported by said frame, a member within said handle, one end of said member engaging certain of said strings, the other end of said member being threaded, a second member engaging said threaded portion, said second member provided with at least one shoulder portion, said second member fitted within a rotatable member, said rotatable member being connected with said second member by means cooperating with said shoulder, whereby upon the rotation of said rotatable member said second member exerts a pull on said first mentioned member thereby tensioning said strings.
15. In a racket, a frame, a hollow handle strings supported by said frame, a member within said handle, one end of said member engaging certain of said strings, a second member engaging the other end of said first mentioned member, said second member pro-
- vided with at least one shoulder portion, said second member fitted within a rotatable cup-shaped member, said cup-shaped member being connected with said second member by means cooperating with said shoulder, said cup-shaped member having a ribbed outer surface to provide increased friction between said cup-shaped member and the hand of the operator when tensioning the strings.
16. In a racket, a frame, a handle, a neck section, a throat member provided with at least one tongue portion interfitting in a recess in said neck section, a fastening element passing through said neck section and said tongue portion transversely to the plane of the face of the racket and extending substantially to the finished surface of the racket so as to be easily accessible for removal.
17. In a racket, a frame, a handle, a neck section, a throat member in mortise and tenon connection with said neck section, and a fastening element passing through said mortise and tenon connection transversely to the plane of the face of the racket and extending substantially to the finished surface of the racket so as to be easily accessible for removal.
18. A racket comprising a handle, a neck portion and a frame, said racket provided with means adapted to receive at least one string, at least a portion of said string receiving means being embedded in a non-metallic plastic body thereby preventing direct contact between said string and said string receiving means.
19. A racket comprising a handle, a neck portion and a frame, a portion of said racket adapted to receive at least one string, a non-metallic coating composition covering at least a part of said string receiving portion, thereby forming a casing over said part thus preventing direct contact between said string and said part.
20. A racket comprising a handle, a neck portion and a frame, said racket provided with means to anchor a string, at least a portion of said string anchoring means covered with a plastic coating, said coating forming a shell adapted to prevent direct contact between said string and said means.
21. A racket comprising a frame, a neck portion, a hollow handle and a string anchoring member, said member adapted to receive at least one string, at least a portion of said string anchoring member positioned within the hollow of said handle, at least a portion of said string anchoring member covered with a coating, said coating forming a shell adapted to prevent direct contact between said string and said anchoring member.
22. A ratchet comprising a handle, a neck portion, a frame and string anchoring member, said member adapted to receive at least one string, at least a portion of said string anchoring member positioned within a recess

in the body of said frame, at least a part of said portion covered with a coating, said coating forming a shell adapted to prevent direct contact between said string and said part of said member.

3 23. In a racket as set forth in claim 21 wherein said string anchoring member is made of metal and said coating comprises a non-metallic composition.

10 24. In a racket as set forth in claim 22 wherein said string anchoring member is made of metal and said coating comprises a non-metallic composition.

15 In testimony whereof I hereunto affix my signature.

JACOB L. KLEINMAN.
